SAFETY FOLDABLE DEVICE FOR HANGING
OUT WET WASH

Dominick Evangelista, Bronx, N. Y.

Application January 7, 1942, Serial No. 425,869

5 Claims. (Cl. 211—119.06)

This invention relates to new and useful improvements in a safety foldable device for hanging out wet wash.

More specifically, the invention proposes the construction of a safety foldable device for hanging wet wash which is adapted to be used in combination with a window frame slidably supporting a pair of adjacent sashes with the foldable device being mounted upon the frame and arranged in a manner to assume an inoperative position to permit the windows to be closed.

Still further it is proposed to so arrange the safety foldable device that it is capable of being extended into the room in the open position of the window to permit wet wash to be engaged upon the wash line without projecting one's body through the open window, and which is arranged to prevent articles of clothing being engaged on the line from dropping out the window to the surface below.

A further object of the invention proposes to characterize the safety foldable device by a pivotally supported casing constructed of channel shaped material and rotatively housing a pair of pulleys over which a clothes line is adapted to be engaged in a manner to permit the clothes line to be advanced in the horizontal position of the casing.

A still further object of the invention proposes a forked portion on the end of one of the links supporting the casing arranged in a manner to engage and take up the slack in the wash line when the casing is pivoted to a vertical inoperative position.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a vertical sectional view taken through a portion of a window frame having a safety foldable device constructed according to this invention and pivoted to an operative position.

Fig. 2 is a view similar to Fig. 1 but with the safety foldable device pivoted to an inoperative position.

Fig. 3 is a horizontal sectional view taken on the line 3—3 of Fig. 1.

Fig. 4 is a vertical sectional view taken substantially on the line 4—4 of Fig. 3.

Fig. 5 is a view looking in the direction of the line 5—5 of Fig. 1.

Fig. 6 is a perspective view of one end of the supporting bracket, per se.

The safety foldable device for hanging out wet wash, according to this invention, is adapted to be mounted upon a portion of a building 10 having a window frame 11 slidably supporting a pair of adjacent window sashes 12 and 13.

The safety foldable device is characterized by a bracket 14 for supporting a pair of vertically spaced stationary members 16 and 17 upon the outside of the frame 11. The bracket 14 is preferably characterized by a pair of vertically spaced angle members 18 attached to the window frame 11 by means of screws 19. A vertical rod 20 has its ends bent at right angles to the length thereof and the ends are securely attached to the angle members 18. The stationary members 16 and 17 are provided with openings through which the rod 20 extends. Set screws 21 are engaged through the stationary members 16 and 17 and engage the rod 20 for holding the stationary members 16 and 17 securely in position upon the rod 20.

An elongated casing 22 having open ends has its top or outer end pivotally attached to the top stationary member 16. The elongated casing 22 is preferably constructed of channel shaped material and has its top or outer end pivotally attached to the top member 16 by means of a pin 23. A handle 24 is mounted on the top wall of the casing 22 and is adapted to be gripped for pivoting the casing about the pin 23.

A pair of rigid links 25 and 26 are pivotally connected end to end by means of a pin 27. The bottom or outer end of the link 26 is pivotally attached to the bottom stationary member 17 by means of a pin 28. The link 25 is constructed of adjacent link sections 25^a which extend along opposite sides of the bottom or inner end of the casing 22. The bottom or inner ends of the link sections 25^a are attached to the bottom or inner end of the casing 22 by means of a pin 29.

The top or inner end of the link 26 is maintained at a position centrally of the top or outer ends of the link sections 25^a by means of spacer elements 30 engaged on the pin 27 on opposite sides of the link 26 and engaging the inner faces of the link sections 25^a.

Pulleys 31 are engaged upon the pins 23 and 29 which pass through the ends of the casing 22 and are maintained in a central position by means of spacer elements 32. A wash line 33 is engaged over the pulleys 31 and is projected through the top portion of the casing 22. When the device is in the position illustrated in Fig. 1

a portion of the wash line 33 projects from the bottom of the casing 22 and is arranged in a convenient manner to receive articles of clothing being placed thereon.

The top or inner end of the bottom or outer link 26 is provided with an enlarged forked portion 34 which engages against the link sections 25^a, as shown in Figs. 1 and 5, in the horizontal position of the casing 22. It is noted that in the position shown in Fig. 1 the links 25 and 26 have been pivoted to a position in which the pin 27 is slightly past dead center so as to maintain the casing 22 in its horizontal position. In this position of the links the forked portion 34 engages the link sections 25^a and prevents further inward pivoting of the pin 27. In the position of the device shown in Fig. 2 the forked portion 34 engages an intermediate portion of the bottom area of the wash line 23 and causes the wash line to be bent to take up the slack in the wash line when the casing 22 is pivoted to its vertical position so as to maintain the extended portion of the wash line substantially taut. It is to be understood that the other end of the wash line 33 is engaged over a pulley, not shown on the drawing, which is supported on an adjacent portion of the building 10 or upon a conventional clothes pole.

The operation of the device is as follows:

The bottom window sash 13 is raised and the handle 24 is gripped to pivot the casing 22 into a position in which its bottom or inner end will be projected into the room to permit articles of clothing to be engaged upon the wash line 33 without extending the body through the open window. After the desired clothing has been engaged on the wash line 33 it is possible to grip the handle 24 and raise upward on the links 25 and 26, freeing the casing 22 to be pivoted downwards, permitting the window 13 to be closed. In this latter position the forked portion 34 will engage and take up the slack in the wash line and the specific arrangement of the pivot points of the various parts are so arranged that the pull upon the wash line 33 would not be able to pull the casing 22 into a position in which it will be projected outwards from the window frame 11.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A safety foldable device for holding a wash line, comprising a pair of vertically spaced stationary members for location outside and adjacent a window frame, an elongated casing having open ends and being pivotally mounted at its top or outer end on the top one of said members to be foldable upwards and downwards, a pair of rigid links pivotally connected end to end and having their outer ends pivotally connected respectively to the bottom or inner end of said casing and to the bottom one of said members to be foldable upwards and downwards, pulleys rotatively mounted on the pivotal points at the ends of said casing for guiding a wash line, and a forked portion on the top or inner end of the bottom or outer one of said pair of links and engaging the top or inner one of said pair of

links when said casing is extended horizontally inwards for holding said links in a stationary locked position and engageable with said wash line when said links are pivoted upwards and said casing is pivoted downwards for locking said device in this latter position by the pivoting tendencies of said casing and links under the weight of said wash line and clothes thereon.

2. A safety foldable device for holding a wash line, comprising a pair of vertically spaced stationary members for location outside and adjacent a window frame, an elongated casing having open ends and being pivotally mounted at its top or outer end on the top one of said members to be foldable upwards and downwards, a pair of rigid links pivotally connected end to end and having their outer ends pivotally connected respectively to the bottom or inner end of said casing and to the bottom one of said members to be foldable upwards and downwards, pulleys rotatively mounted on the pivotal points at the ends of said casing for guiding a wash line, and a forked portion on the top or inner end of the bottom or outer one of said pair of links and engaging the top or inner one of said pair of links when said casing is extended horizontally inwards for holding said links in a stationary locked position and engageable with said wash line when said links are pivoted upwards and said casing is pivoted downwards for locking said device in this latter position by the pivoting tendencies of said casing and links under the weight of said wash line and clothes thereon, said vertically spaced stationary members being mounted upon a bracket attached to said frame.

3. A safety foldable device for holding a wash line, comprising a pair of vertically spaced stationary members for location outside and adjacent a window frame, an elongated casing having open ends and being pivotally mounted at its top or outer end on the top one of said members to be foldable upwards and downwards, a pair of rigid links pivotally connected end to end and having their outer ends pivotally connected respectively to the bottom or inner end of said casing and to the bottom one of said members to be foldable upwards and downwards, pulleys rotatively mounted on the pivotal points at the ends of said casing for guiding a wash line, and a forked portion on the top or inner end of the bottom or outer one of said pair of links and engaging the top or inner one of said pair of links when said casing is extended horizontally inwards for holding said links in a stationary locked position and engageable with said wash line when said links are pivoted upwards and said casing is pivoted downwards for locking said device in this latter position by the pivoting tendencies of said casing and links under the weight of said wash line and clothes thereon, said vertically spaced stationary members being mounted upon a bracket attached to said frame, said bracket comprising L-shaped members attached to said frame, a rod supported upon said L-shaped members, and said stationary members being provided with openings through which said rod extends, and means for securely attaching said members to said rod.

4. A safety foldable device for holding a wash line, comprising a pair of vertically spaced stationary members for location outside and adjacent a window frame, an elongated casing having open ends and being pivotally mounted at its top or outer end on the top one of said members to be

foldable upwards and downwards, a pair of rigid links pivotally connected end to end and having their outer ends pivotally connected respectively to the bottom or inner end of said casing and to the bottom one of said members to be foldable upwards and downwards, pulleys rotatively mounted on the pivotal points at the ends of said casing for guiding a wash line, and a forked portion on the top or inner end of the bottom or outer one of said pair of links and engaging the top or inner one of said pair of links when said casing is extended horizontally inwards for holding said links in a stationary locked position and engageable with said wash line when said links are pivoted upwards and said casing is pivoted downwards for locking said device in this latter position by the pivoting tendencies of said casing and links under the weight of said wash line and clothes thereon, said vertically spaced stationary members being mounted upon a bracket attached to said frame, said bracket comprising L-shaped members attached to said frame, a rod supported upon said L-shaped members, and said stationary members being provided with openings through which said rod extends, and means for securely attaching said members to said rod, said latter means comprising set screws extending through said stationary members and engaging said rods.

5. A safety foldable device for holding a wash line, comprising a pair of vertically spaced stationary members for location outside and adjacent a window frame, an elongated casing having open ends and being pivotally mounted at its top or outer end on the top one of said members to be foldable upwards and downwards, a pair of rigid links pivotally connected end to end and having their outer ends pivotally connected respectively to the bottom or inner end of said casing and to the bottom one of said members to be foldable upwards and downwards, pulleys rotatively mounted on the pivotal points at the ends of said casing for guiding a wash line, and a forked portion on the top or inner end of the bottom or outer one of said pair of links and engaging the top or inner one of said pair of links when said casing is extended horizontally inwards for holding said links in a stationary locked position and engageable with said wash line when said links are pivoted upwards and said casing is pivoted downwards for locking said device in this latter position by the pivoting tendencies of said casing and links under the weight of said wash line and clothes thereon, said casing being constructed of a channel shaped member and having a handle mounted on its top wall by which it may be pivoted.
